UNITED STATES PATENT OFFICE.

LEWIS HALLOCK NASH, OF SOUTH NORWALK, CONNECTICUT, ASSIGNOR
TO THE NATIONAL METER COMPANY, OF NEW YORK, N. Y.

SPEED-TRANSMITTING DEVICE.

SPECIFICATION forming part of Letters Patent No. 638,668, dated December 5, 1899.

Application filed January 10, 1899. Serial No. 701,715. (No model.)

To all whom it may concern:

Be it known that I, LEWIS HALLOCK NASH, a citizen of the United States, residing at South Norwalk, in the county of Fairfield and State 5 of Connecticut, have invented certain new and useful Improvements in Speed-Transmitting Devices, of which the following is a specification.

My invention relates to speed-transmitting devices; and it consists of certain novel parts and combinations of parts pointed out in the concluding claims.

In the accompanying drawings I have shown a device embodying my invention in the form 15 at present preferred by me. The following is a description of the device shown in the drawings; but it will be understood that various modifications and changes may be made without departing from the spirit of my invention and without exceeding the scope of the claims.

Referring to the drawings, Figure 1 is a vertical view of my speed-transmitting device. Fig. 2 is a section on the line 2 2 of Fig. 1. 25 3 is a driving-shaft connected to a source of power. 4 is a fly-wheel keyed to said shaft, having a rim 5, which is turned upon its inside surface to form a friction-bearing for a friction-clutch.

30 6 is a driven shaft, and 7 a fly-wheel keyed to said shaft. This fly-wheel 7 has arms or spokes which support bearing-pins 8, upon which pins levers 9 are hinged. The outer edge of each lever carries a shoe 11, which shoe bears upon the inner surface of the rim 5 of the driving-wheel. These levers 9 are controlled, as hereinafter described, by set-screws 12, fixed to an intermediate wheel 13 and springs 14, each having one end attached 35 to a lever 9 and at the other to a lug 15 upon said intermediate wheel.

The intermediate wheel 13 is loosely mounted on its support, being held in place by plate 23, and carries studs 16 16, which serve as fulcrums for governor-weights 17 17, controlled by springs 18 18, attached to lugs 19 19. A link 20 connects the two weights, so that they act together. These weights 17 carry shoes 22 22, which bear upon the inner surface of 40 the rim 5.

The operation of the device is as follows:

Considering first the intermediate wheel 13, it will be seen that the only means of driving the wheel are the shoes 22 in frictional contact with the rim of the driving-wheel, and 55 that the friction between the two is regulated by the governor-weights 17 acting in connection with springs 18 in such a manner that when the intermediate wheel exceeds a predetermined speed centrifugal force acting on 60 the weights 17 overcomes the force of the springs 18 and withdraws the shoes 22 more or less from contact with the rim 5. The loosely-mounted intermediate wheel by its inertia overcomes any sudden tendency to acceleration or retardation, so that change of speed cannot be sudden, while the governor establishes what the normal speed shall be. Considering next the driven wheel 7, it will be seen that the motion of the driving part is 65 communicated to this driven part by the shoes 11 11 11 11 in friction contact with the rim of the driving-wheel. The levers 9, to which these shoes are attached, being controlled by springs 14 and set-screws 12, attached to the intermediate part 13, if the intermediate part tends to go faster than the driven wheel it has the effect of immediately pressing the shoes 11 in contact with the rim 5, and this immediately causes the wheel 7 70 to accelerate its velocity until it equals the velocity of the wheel 13. On the other hand, if the wheel 13 tends to go slower than the wheel 7 it has the effect of instantly diminishing or withdrawing pressure upon the shoes 75 11, and thus causing the velocity of the wheel 7 to diminish. It therefore of necessity follows that the wheel 7 must revolve at substantially the same velocity as the wheel 13. By reason of the inertia of this intermediate 80 wheel and the fact that it transmits a small amount of force it is easy to control it and to secure a uniform speed without bringing upon it any severe strains. Said intermediate part also acts as a power-multiplying device through the lever 9, by which a small amount of force exerted by the centrifugal mechanism 17 and 18 is greatly multiplied in 85 acting upon the friction mechanism of the wheel 7.

Many of the details and combinations illustrated and above described are not essential

to my several inventions, broadly considered. All this will be indicated in the concluding claims, where the omission of an element or the omission of reference to the detail features of the elements mentioned is intended to be a formal declaration of the fact that the omitted elements or features are not essential to the inventions therein severally covered.

10 What I claim is—

1. In a speed-transmitting mechanism, the combination of a driving part, an intermediate part loosely mounted on its support and having a friction device bearing upon the driving part and a governor by means of which said friction device is controlled, a driven part having a friction device also bearing upon the driving part and mechanism connecting the intermediate part with the friction device of the driven part by means of which it is controlled.
- 15 2. In a speed-transmitting mechanism, the combination with the driving and driven parts of an intermediate wheel loosely mounted, a governor carried by said intermediate wheel having friction relation with the driving part,
- 20
- 25

and a friction-clutch carried by the driven part and operated by said intermediate part.

3. In a speed-transmitting device, the combination with the driving part, of an intermediate part provided with a centrifugal governor and a friction-shoe controlled by said governor and bearing upon the driving part and a driven part carrying a lever provided with a friction-shoe in contact with the driving part, said lever being acted upon by the power transmitted through the intermediate part to maintain friction contact between the shoe of the last-mentioned part and the driving part.

4. In a speed-transmitting mechanism, the combination with the driving part 5, of an intermediate part 13, centrifugal governor 17, 18, shoe 22, driven part 7 carrying friction device 9 controlled by a stud 12, attached to the 45 intermediate part.

In testimony whereof I have hereunto signed this specification.

LEWIS HALLOCK NASH.
